CLOSURE CONSTRUCTION

Clyde W. Kelly, Detroit, Mich., assignor to Detroit Steel Products Company, Detroit, Mich., a corporation of Michigan

Application November 11, 1942, Serial No. 465,278

1 Claim. (Cl. 292—240)

The invention relates to closure constructions and refers more particularly to water-tight doors, hatches, and the like, for use in ships.

The invention has for some of its objects to provide an improved closure construction in which the bodies of the member having the opening and of the closure for the opening are approximately in the same plane; to provide a closure construction which is water-tight; and to provide a closure construction which is so made that it will readily withstand the usual pressure to which it may be subjected.

The invention has for other objects to provide the closure construction with an improved dog for use in locking the closure in closed position; to so form the dog that it may be readily mounted in predetermined position on either the member with the opening or the closure; and to provide the dog with a stop which forms a part of the base of the dog, thereby facilitating making the complete assembly.

With these and other objects in view, the invention resides in the novel features of construction and combinations and arrangements of parts as more fully hereinafter set forth.

In the drawings:

Figure 1 is an elevation of a closure construction embodying the invention;

Figure 2 is a cross section on the line 2—2 of Figure 1;

Figure 3 is an enlarged elevation at the side opposite that in Figure 1 of a portion of the closure construction;

Figure 4 is a cross section on the line 4—4 of Figure 3;

Figure 5 is a cross section on the line 5—5 of Figure 3;

Figure 6 is a view similar to Figure 5 showing a modification;

Figure 7 is a view similar to Figure 3 showing a modification;

Figure 8 is a cross section on the line 8—8 of Figure 7;

Figure 9 is a view similar to Figure 3 showing another modification;

Figure 10 is a cross section on the line 10—10 of Figure 9.

The invention is applicable to closure constructions, such as doors, hatches, and the like, which comprise a member having an opening, a closure for the opening, and means for holding the closure in closed position. In the present instance, a water-tight door for use in a ship as, for example, in a ship bulkhead, is shown.

In detail, the member having the opening is

the frame 1 comprising the endless flat body 2, the endless flange 3 extending transversely of the body beyond both sides thereof and bordering the opening, and the curved connecting portion 4 between one edge of the flange and the adjacent edge of the body. The closure for the opening is the door 5 having the flat body 6 and the endless channel 7 at the edge of the body and registering with and opening toward the free edge of the flange 3. 8 is an endless sealing member, preferably in the nature of a rubber gasket, located in the channel 7, the latter being dovetailed to hold the gasket from accidental disengagement. The channel is laterally offset from the door body in a direction away from the frame so that in the closed position of the door the channel cooperates with the transverse flange of the frame to position the door body approximately in the plane of the frame body, it being noted that the two bodies are in nearly the same plane.

The door is preferably hinged along one side to the frame by the hinges 9 each of which comprises a hinge leaf 10 preferably welded to the door body and channel, the hinge leaves 11 at opposite sides of the hinge leaf 10 and preferably welded to the frame body, and the pin 12 extending through the leaves.

For holding the door in closed position with the transverse flange of the frame making a water-tight connection with the sealing gasket, I have provided the series of dogs 13 which are spaced around the frame to engage the door at a number of spaced zones. The dogs are alike and, as shown particularly in Figures 3, 4 and 5, each dog comprises the tubular member 14 in the nature of a pipe and the base member 15 in the nature of a plate encircling and permanently secured to the tubular member in predetermined position as by being welded thereto at 16. As a result, the pipe and plate form a unit base which when mounted on the frame body 2 has the pipe 14 extending transversely of the frame body through a hole of slightly larger diameter and also has the plate 15 abutting the frame body at the side of the connecting portion 4. The plate is formed at diametrically opposite sides of the pipe with the accurately located holes 17 for receiving the rivets 18 which extend through the holes 19 in the frame body. The rivet holes 19 are predeterminedly located on the frame body so that when the unit base is assembled with the frame body and the rivets are headed the unit base is accurately positioned on the frame body by means of the plate 15. More particularly,

the plate effects the predetermined positioning by abutting the frame body and by engaging the rivets. The rivets make a water-tight connection with the frame base so that no water can leak between the rivets and the frame base. The unit base is permanently secured to the frame base after the unit base has been predeterminedly positioned and the rivets have been headed by welding the outer side of the pipe 14 to the side of the frame base opposite the plate 15 at 20. The weld is endless and seals the joint between the pipe and the frame base to make the same water-tight. The dog also comprises the shaft 21 which extends through the pipe 14 and is journaled in the end bushings 22 in the pipe between which bushings is located suitable sealing material under pressure. The dog also comprises the hand levers 23 and 24 which are fixed on the shaft 21 at opposite sides of the frame with the hand lever 23 detachably secured to the shaft and the hand lever 24 integral with the shaft. The shaft 21 is preferably formed with diametrically opposite flats for cooperating with corresponding flats formed in the hole of the hub of the hand lever 23, whereby the hand lever can rotate the shaft. The hand lever 24 constitutes the dog arm having the boss 25 for engaging the wedge strike 26. The wedge strike is fixedly secured to the web of the channel 7.

To limit swinging movement of the hand levers 23 and 24 when swinging to locking position so that the boss 25 cannot pass completely over the wedge strike 26, the plate 15 of the unit base is formed with the transverse ear 27 which is engageable with and forms a stop for the hand lever 23 when the boss engages the rear end of the wedge strike. To hold the hand levers in released position, at which time the hand lever 24 clears the door 5, the plate 15 is provided with the transverse ear 28 which is substantially diametrically opposite the ear 27. This ear has secured thereto the curved spring 29 which forms a stop for the hand lever 23 when in released position. The spring is formed with the generally bowed portion 30 for receiving the hand lever and resiliently holding this hand lever when it is in released position. The spring is also formed with the upwardly bowed portion 31 for facilitating the riding of the hand lever over the lower surface of the spring while the hand lever is being moved to released position.

With this construction of dog, its assembly on the frame is greatly facilitated since the unit base comprising the pipe 14 and the plate 15 may be readily mounted on the frame base in predetermined position, as determined by the plate engaging the frame base and the rivets which essentially temporarily secure the unit base to the frame base. Inasmuch as the stops for limiting the swinging movement of the hand lever to locking position and released position also form parts of the unit base, the necessity of several complicated fixtures for predeterminedly positioning the dog and the stops on the frame base is eliminated and the complete assembly is greatly facilitated and the speed of assembly is greatly increased.

Instead of using rivets for predeterminedly positioning the dogs on the frame, cooperating bosses may be used, as shown particularly in Figure 6. The unit base plate 32 is provided, as shown, with the diametrically opposite depressed bosses 33 nesting in the depressed bosses 34 formed in the body 35 of the frame. The latter

bosses are accurately located and serve to accurately position the unit base while it is being spot-welded to the frame. The spot welds hold the unit base and frame together while the unit base is being permanently secured to the frame base by welding the outer side of the unit base pipe to the frame base at 36. The weld 36 is endless and seals the joint to make the assembly water-tight. This construction is generally preferable to that using rivets since it may be more easily made water-tight.

In the modification illustrated in Figures 7 and 8, the dogs are mounted on the door 37. Each dog has the unit base comprising the pipe 38 and the plate 39 welded to each other with the plate forming a shoulder abutting one side of the door body 40 and the unit base permanently secured to the other side of the door body as by being externally welded thereto at 41. The plate and door body are formed with either predeterminedly located rivet holes for receiving positioning rivets or with predeterminedly located cooperating bosses for predeterminedly positioning one on the other, the bosses being preferable. The plate instead of being formed with two ears is formed with the transverse ear 42 which has secured thereto the spring 43 having the angular portion 44 for cooperating with the end of the ear 42 to partially embrace the dog arm 45 when the latter is in released position. The dog arm is fixed upon the shaft 46 which extends through and is journaled in the pipe 38 in the same manner as the shaft 21. Also fixedly secured to the shaft are the hand levers 47 and 48. The construction, including the shaft and hand levers, is the same as that illustrated particularly in Figures 3 and 4. Also, the construction for securing the dog arm to the shaft to rotate therewith is the same as the construction for securing the hand lever 23 to the shaft 21. 49 is the wedge strike which is secured to the angle-shaped liner 50 and is engageable with the dog arm 45. The liner is secured, as by being welded, to the body of the frame and to the connecting portion between the transverse flange and the body of the frame. The wedge strike has the stop 51 for limiting the swinging movement of the dog arm so that it cannot pass completely over the wedge strike.

Figures 9 and 10 illustrate another modification which differs essentially in forming the dog arm 52, the hand lever 53 and the shaft 54 integral, with the dog arm extending from the shaft in a direction opposite the hand lever. In this modification the hand lever 55 is detachably secured to the shaft. The remainder of the construction, including the unit base, the wedge strike, and the manner of securing the unit and wedge strike in place, is substantially the same as illustrated in Figures 7 and 8.

What I claim as my invention is:

A dog for a closure construction having a member with an opening and a closure member for the opening, said dog comprising a tubular member and a base member extending transversely of said tubular member and permanently secured thereto and forming therewith a unit base, said base member abutting one side of one of the members of the closure construction and having a predeterminedly positioned stop forming a part thereof, said tubular member extending transversely through the last mentioned member of the closure construction, cooperating bosses on said base member and the last mentioned member of the closure construction for predeterminedly

positioning said base member relative to the last mentioned member of the closure construction and thereby predeterminedly positioning said unit base on the last mentioned member of the closure construction, endless weld material at the other side of the last mentioned member of the closure construction for permanently secur-

ing said tubular member to said last mentioned member of the closure construction and sealing the joint therebetween, a shaft journaled in said tubular member, and a swinging arm secured to said shaft and engageable with said stop for limiting swinging movement of said arm.

CLYDE W. KELLY.
